Primary Examiner — Brian N. Vinson(74) *Attorney, Agent, or Firm* — Staas & Halsey LLP(57) **CLAIM**

The ornamental design for a lens for light emitting diode, as shown.

DESCRIPTION

FIG. 1 is a front view of the lens for light emitting diode showing the new design;

FIG. 2 is a rear view;

FIG. 3 is a right side view, the left side view being a mirror image thereof;

FIG. 4 is a top view;

FIG. 5 is a bottom view;

FIG. 6 is a cross-sectional view taken along line A-A of FIG. 2; and,

FIG. 7 is a rear, top and right side perspective view.

1 Claim, 7 Drawing Sheets(56)
